UNITED STATES PATENT OFFICE.

GEORGE H. MILLEN AND EDWARD MOUSSEAU, OF HULL, QUEBEC, CANADA.

MATCH-SPLINT MACHINE.

SPECIFICATION forming part of Letters Patent No. 295,191, dated March 18, 1884.

Application filed November 24, 1883. (No model.)

To all whom it may concern:

Be it known that we, GEORGE HENRY MILLEN and EDWARD MOUSSEAU, both of Hull, in the Province of Quebec, in the Dominion 5 of Canada, have jointly invented certain new and useful Improvements in Match-Splint Machines; and we do hereby declare that the following is a full, clear, and exact description of the same.

10 Our invention has for its object to facilitate the manufacture of match-splints by scoring and slicing the splint-blocks by knives moving continuously in one direction in a horizontal plane under a row of boxes automatically 15 feeding the splint-blocks to the knives, whereby any number of knives and any number of feed-boxes may be used, to either increase or diminish the capacity of the machine, and the knives be operated without much loss of time 20 and waste of motive power.

Our invention consists of a frame or stand having an endless apron composed of apertured plates or rectangular links hinged together, and sliding over or along two parallel 25 flat rails secured to the top of the frame, on which is a row of boxes feeding the splint-blocks automatically, said plates or links severally having knives to alternately score the splint-blocks and slice off the scored portion 30 horizontally, thereby making the splints. The splints, after being cut off by the slicing-knives, fall through the apron into troughs having an endless-belt bottom to collect the splints at one end of the trough.

35 Figure 1 is a side elevation of our machine. Fig. 2 is a top view of the same. Fig. 3 is an enlarged transverse section on line $x-x$, Fig. 2. Fig. 4 is an enlarged transverse sectional view of the top rails of the frame, and a portion of the apron, and one side of a feed box and gear in elevation. Fig. 5 is a side elevation of Fig. 4. Fig. 6 is a top view of the same. Fig. 7 is an enlarged top view of two plates or links of the apron, showing the scoring and slicing knives; and Fig. 8 is a longitudinal vertical section of the same.

1 is the rectangular frame or stand of the machine, of any suitable construction, having two flat parallel rails, 2 2', secured longitudinally to the top.

3 is a hexagonal-sided wheel journaled to

one end of the frame, and 4 is a like wheel journaled in adjustable boxes sliding on brackets 4', secured to the opposite end of the frame, said boxes adjustable by set-screws. The 55 wheels 3 4 carry an endless apron, which is driven by wheel 3 in any suitable manner, a mode being shown in the drawings consisting of gear-wheels, belts, pulleys, and shafting.

The endless apron is composed of square 60 links or apertured plates 5, hinged together. The plates of the apron are alternately provided over the aperture therein with vertical parallel knives 15 of sufficient number to cut the width of the splint-block, and at a distance apart corresponding to one side of the square of the splints to be cut. These knives are longer than the splints to be cut, and score the block endwise horizontally. The cutting-edge of each knife inclines upwardly from the 70 forward end, to gradually cut into the splint-block vertically, whereby a straight cut or score is insured across any crookedness in the grain of the wood of the splint-block, and thereby each splint will have two parallel scored 75 sides and be uniformly straight. The aperture in the plate prevents accumulation of wood fiber between the knives 15. The knives 15 fit into slots in the plate, or they may be inserted in a frame fitting into the aperture and 80 held by clamp-screws.

To the plates of the apron intervening the plates having the scoring-knives is secured horizontally a flat slicing-knife, 16, preferably having a V cutting-edge, and in two parts, for 85 convenience in sharpening. Each knife 16 is bolted to its respective plate at an elevation corresponding to the height of the scoring-knives, and said knives 16 cut off the portion of the splint-block scored by the knives 15. 90 The V-edged knife 16 is preferable, because it will cut diagonally and inward, and cut smooth without following the grain of the wood, thereby insuring a straight cut, and make the splints straight. The knives 16 95 being set over the aperture in the plate, said aperture forms a throat, 19, through which the splints pass after being severed from the splint-block by the slicing of the knives 16. The sides of each plate 5 are chased or rabbed, as seen in section, Fig. 4, to bear upon 100 and slide along and between the rails 2 2', to

cause the upper band of the apron to run in a horizontal plane under feed-boxes 6, bridging the space between the rails 2 2', and bolted thereto at suitable distances apart. Each of 5 the feed boxes or hoppers has an opening in opposite sides, in which turn feed-rollers 8 8', respectively keyed on shafts 9 9', journaled to the feed boxes, and said shafts carry at one end cog-wheels 10 10', meshing together and 10 driven by a ratchet-wheel, 11, on shaft 10, which ratchet-wheel and cog-wheels are moved intermittently by pawl 12, sliding endwise in a box or casing, 12', secured to rail 2', and which pawl is lifted by passage thereunder of 15 cam 14, projecting from one side of the plates of the apron carrying the scoring-knives 15, whereby the rollers 8 8' are intermittently rotated to feed the splint-block in the box to the knives 15.

20 13 is a stop-pawl, pivoted at its lower end to casing 12', to prevent retractive movement of ratchet-wheel 11 while pawl 12 is being retracted to a position to be again lifted by contact of the succeeding cam 14. This retractive movement is effected by a coiled spring, 7, 25 one end secured to an arm projecting from the pawl, and the other end to an arm projecting from the casing or boxing containing the pawl.

30 The plates or links 5 of the apron, provided with a slicing-knife, are not provided with a cam; hence the feed-gear of each feed-box and the splint-block therein remain stationary while the scored portion is being removed by 35 the slicing-knife, and the cams 14 being a little in advance of the scoring-knives, the feed operation takes place only and immediately before the scoring-knives reach the block. The splints, after being sliced off by the knives 40 16, fall through the aperture 19 in the plate into a trough, 17, having an endless-belt bottom, 18, running over pulleys 19', journaled to frame 1. Said trough and belt are at a right angle to the course of the apron. The inner 45 end of the trough, vertical with the feed-box, catches the splints as they drop through the apron, the belt then conveying them to the opposite end of the trough, which is closed by an inclined end to collect the splints compactly.

50 A machine or apparatus such as we describe may have any number of feed-boxes 6, and the apron may be composed of any number of knife-plates 5, hinged together, and 55 the feed-boxes may be distanced apart so that all the knives will not be cutting at the same time, thereby economizing motive power.

56 In making the apron, we prefer to have a blank plate or link intervening the plates or 60 links carrying the scoring-knives and slicing-knives; but such may be dispensed with.

We are aware that automatic feed-boxes such as we describe have been used in match-making machines having reciprocating knives to score and slice the splint-block, and that 65 cutter-blocks for slicing hoop-stuff and boards have been attached to endless hauling-chains; but such cutter-block has not formed part of the chain.

We are also aware that endless belt-conveyors have been used in match-splint machines having reciprocating scoring and slicing knives; but in such case they were not applied to convey the splints directly, a series of conveyer-belts arranged anglewise being 75 used.

We claim as our invention—

1. The endless apron composed of apertured plates 5, or rectangular links hinged together having scoring-knives 15 and slicing-knives 80 16, alternately, in combination with frame 1, having rails 2 2', wheels 3 4, and feed-boxes 6, as set forth, for the purpose described.

2. The combination, with frame 1, having parallel rails 2 2', of the endless apron composed of plates or links 5, hinged together, having scoring-knives 15 and slicing-knives 16, alternately arranged, a series or row of feed-boxes, 6, having feed-rollers 8 8', and ratchet-wheel and pawl intermittently operated by 90 cams 14 on the apron, to automatically feed the splint-block to the scoring-knives, and subsequently slice the splints, as set forth.

3. The endless apron composed of apertured plates or links 5, hinged together, having alternately scoring and slicing knives, the plates having the scoring-knives provided with cams 14, in combination with feed-boxes 6 and intermediate ratchet-gear and rollers, to feed the splint-blocks by the movement of the apron, 95 as set forth.

4. The combination, with frame 1, having rails 2 2' and polygonal wheels 3 4, of the endless apron composed of apertured plates or links 5, hinged together, alternately having 105 slicing-knives 16 and scoring-knives 15, feed-boxes 6, having an automatic feed-gear operated by cams 14 on the apron, and troughs 17, having an inclined end and endless-belt bottom, 18, whereby the splint-blocks are automatically fed and successively scored and sliced 110 by knives moving in a continuous plane, and the splints collected at the end of the troughs, substantially as described and set forth.

In testimony whereof we have signed this 115 specification in the presence of witnesses.

GEO. H. MILLEN.
ED. MOUSSEAU.

In presence of—
JOHN GRIST,
R. P. KING.
